(57) **CLAIM**

I claim the ornamental design for a mold swab testing tip, as shown and described.

DESCRIPTION

FIG. 1 is a bottom perspective view of a mold swab testing tip, showing my new design;

FIG. 2 is an enlarged top perspective view thereof;

FIG. 3 is a left-side elevational view of FIG. 2;

FIG. 4 is a right-side elevational view of FIG. 2;

FIG. 5 is a front elevational view of FIG. 2, the rear elevational view being a mirror image thereof;

FIG. 6 is a top plan view of FIG. 2; and,

FIG. 7 is a bottom plan view of FIG. 2.

The broken lines showing a handle and mold swab in FIG. 1 illustrate environment of the mold swab testing tip and form no part of the claimed design. The broken lines shown on the claimed portion in FIG. 1 and the broken lines shown in FIGS. 3 and 4 illustrate portions of the mold swab testing tip that form no part of the claimed design.
